UNITED STATES PATENT OFFICE

2,482,613

MANUFACTURE OF UNIT STRIP ASSEMBLIES

Andrew L. Erickson, Cincinnati, Ohio, assignor
to Ditto, Incorporated, Chicago, Ill., a corpora-
tion of West Virginia

Application May 29, 1944, Serial No. 537,962

9 Claims. (Cl. 270—52)

1

The present invention relates to the manufacture of unit strip assemblies and has as its principal object the provision of a novel and effective method whereby a web of paper or other sheet-like material can be divided up into a series of sheets assembled in overlapped relation with like portions of each sheet below the top sheet exposed to view from either side of the assembly.

Unit strip assemblies as referred to herein comprise assemblies of a plurality of sheets arranged so that each sheet from the bottom to the top of a series is offset in the same direction, thereby leaving a portion of the lower sheet exposed at one side edge so that the exposed portion of each of the sheets may receive an impression from a master copy, a printing press or other means in a single duplicating or printing operation while the several sheets are held together as a unit. According to the present invention it is contemplated that assemblies of this character may be made from a web or a plurality of webs. The assemblies may be of plain material or the webs may contain information previously printed, typed or otherwise applied thereto. For example, the invention is particularly applicable to the manufacture of unit strip assemblies of checks which are printed while the paper is still in web form. The printing is arranged on the checks so as to leave space at one edge for insertion of such material as the name of the payee, the Social Security number, and the amount of the check.

According to my invention I provide the printed web with transverse slits separating the several printed forms thereon and I then arrange a series of lengths of such printed web so that their leading edges are offset. The transverse slits are equally spaced from the leading edges of the several lengths so that if the several lengths are laid one upon each other with the leading edge of each sheet from the bottom to the top set back a half inch all of the transverse slits in the group will be offset the same amount. It is possible by this method to superpose any desired number of lengths within reason. For example, there may be five to fifty lengths of the printed web. The transverse slits are terminated short of the side edges of the web so that there is ample stock to enable the lengths to be handled as individual webs. In order to make unit strip assemblies from the several lengths suitable means are provided along the side edges for securing the superposed lengths to each other. A particularly advan-

2

tageous means for effecting this result is the application of small dots of adhesive to one surface of each length adjacent the side edges thereof and between the transverse slits.

The objects and advantages of the present invention will appear more fully as the description proceeds, reference being had to the accompanying drawings wherein a preferred form of the invention is shown. It is to be understood however that the drawings and description are illustrative only and are not to be taken as limiting the invention except insofar as it is limited by the claims.

In the drawings:

15 Fig. 1 is a view in side elevation of a web printing device by which the several forms which are to be assembled in the unit strip assemblies may be printed;

20 Fig. 2 is a sectional view taken on the line 2—2 of Fig. 1;

Fig. 3 is a sectional view taken substantially on the line 3—3 of Fig. 2;

Fig. 4 is a plan view of a web made in accordance with my invention;

25 Fig. 5 is a sectional view taken substantially on the line 5—5 of Fig. 6 illustrating an adhesive applying and web length assembling and trimming device embodied in my invention;

Fig. 6 is a view taken substantially on the line 30 6—6 of Fig. 5;

Fig. 7 is a fragmentary perspective view of a plurality of lengths of the printed web illustrating how the several lengths are superposed and attached to each other;

35 Fig. 8 is a transverse sectional view taken substantially on the line 8—8 of Fig. 5;

Fig. 9 is a sectional view taken substantially on the line 9—9 of Fig. 5;

Fig. 10 is a fragmentary sectional view taken 40 on the line 10—10 of Fig. 12 illustrating the trimming operation;

Fig. 11 is a sectional view taken on the line 45 11—11 of Fig. 5; and

Fig. 12 is a sectional view taken on the line 12—12 of Fig. 5.

Referring now in detail to the drawings, the mechanism shown in Figs. 1, 2 and 3 is arranged to take a web 15 of paper from a roll 16 and direct it between the rollers 17 and 18 of a printing couple. Any other suitable printing means may be used. The roller 17 is inked by a group 19 of inking rollers in any well known manner. After the web is printed upon it passes next to a suitable mechanism 20 which is adapted to punch a multiplicity of evenly spaced apertures in the

side edges of the web. As illustrated, the punching is accomplished by an upper roller 21 and a lower roller 22 carrying cooperating die elements 23 and punch elements 24. Provision is made for punching rows of apertures along both side edges of the web although in certain cases one series of apertures may be sufficient. Other registering means may also be provided. The web, upon leaving the mechanism 20, next passes to a slitting mechanism 25 which comprises an upper 10 drum 26 and a lower drum 27. The lower drum is provided with a plurality of grooved blocks 28 adapted to receive slitting knives 29 that are mounted in the upper drum 26. The slitting knives are controlled in their operation by suitable cams 30 which are mounted on a shaft 31, the drum 26 of course being rotatably mounted on the shaft 31 and there being two of the cams 30 within the drum. Each of the knives 29 has two stems 32 extending inwardly therefrom and each stem carries a roller 33 that rides in the cam 30. The stems have springs 34 thereon held in compression between the knives 29 and plates 35 fastened on the drum so that the springs tend to force the knives outwardly into slitting position. It will be observed from Fig. 3 that when a knif is in the lowermost position the cams 30 permit the springs 34 to force the knife 29 downward to thus make a transverse slit in the web 15. As shown best in Figs. 2 and 4, the length of the slitting knife 29 is such as to provide a slit 36 in the web which terminates inside the rows 37 and 38 of apertures punched in the side edges of the web by the mechanism 20. It is within the scope of my invention to make the transverse slits by a line of perforations or other weakening of the web sufficiently to cause it to readily break along the transverse line.

After the printed, punched and slitted web leaves the slitting mechanism 25 it is wound upon a roller 39, there being a pressure roller 40 to drive the roller 39.

The drive mechanism for the printing, punching and slitting devices just described comprises a motor 41, a speed reducer 42, a sprocket wheel 43, a chain 44, and a sprocket wheel 45 which is fixed to a shaft 46 of the drum 27. The drum 27 has a gear 47 attached thereto. This gear meshes with a gear 48 on the drum 26 so as to drive the slitting drum. The gear 47 is also connected by an intermediate pinion 49 to a gear 50 on the roller 22. The gear 50 meshes with a gear 51 on the roller 21 so that the rollers 21 and 22 will be driven in unison. The gear 50 also meshes with a pinion 52 that in turn meshes with a gear 53 on the lower roller 18 of the printing couple. The gear 53 meshes with a gear 54 on the upper roller 17 of the printing couple and the gear 54 in turn meshes with suitable gears 55 and 56 which drive the inking rollers. All of the mechanism just described is carried by a framework 58 of any suitable construction.

Referring now to Fig. 4, the web 15 as shown first receives printed matter from the printing couple. Next it receives the rows of punched apertures 37 and 38 from the mechanism 20 and finally it receives the transverse slits 36 from the mechanism 25. The particular printing, punching and slitting mechanism shown may be combined or varied in accordance with good production practices within the scope of my invention. The printed web is wound on the roller 39 until the desired length for the next step in the process has been provided. When a plurality of rollers 39 are provided with the desired lengths of print-

ed, punched and slitted web the several rollers are then transferred to the mechanism illustrated in Figs. 5 to 12, inclusive.

In Fig. 5 I have illustrated five rollers 39 as mounted in notches 59 which are provided in two vertical side plates 60 and 61 (see Fig. 6). The side plates 60 and 61 are part of a framework 62 which mounts a plurality of adhesive applying devices 63 and which also mounts suitable guide rollers 64 and 65 to guide the webs from the rollers 39 past the adhesive applying devices. The mechanism shown applies adhesive along both side edges of the webs. However, one row of adhesive dots may be sufficient for some purposes. The framework 62 includes a base 66 and side walls 67, 68, 69 and 70. Suitable upright angular frame members 71, 72, 73, 74, 75 and 76 are provided for supporting the side walls and the rollers 64 and 65.

The base 66 has a portion 77 attached thereto, which portion is provided with side frames 78 that mount a drum 79. The drum 79 is carried on a shaft 80 which is journaled in the side frames 78. This drum is provided with a multiplicity of pins 81 spaced apart to correspond to the punched openings 37 and 38 of the web, there being a row of pins 81 at each end of the drum. In initially applying the webs carried by the rollers 39 to the mechanism just described, the webs are led from the rollers 39 over the guiding rollers 64 and 65 to the drum 79 where the bottom web 15a is first attached to the drum 79 by having the openings 37 and 38 therein engaged with the pins 81. The next web 15b is then attached to the drum in the same fashion but with its leading edge set back from the leading edge of the web 15a an amount equal to a multiple of the distance between the pins 81. The exact amount depends upon the amount of overlap ultimately desired in the unit strip assembly. For example, if the punched openings 37 and 38 are one-quarter inch apart and it is desired to have one-half inch overlap the web 15b will have its leading edge set back to the second pin from where the leading edge of the web 15a was attached. In a like manner the webs 15c, 15d and 15e will be attached to the drum 79. This manner of attaching the webs is illustrated in Fig. 10.

Referring now to the adhesive applying mechanism, this mechanism is best shown by reference to Figs. 5, 6, 8 and 9. The adhesive applying devices 63 are all alike but they are so mounted as to be equally spaced from the leading edges of the respective webs to which they are to apply adhesive. This is necessary in order to have the adhesive applied at the correct spots between the transverse slits 36 in the webs 15. In order to mount the adhesive applying devices 63 and operate them I provide two stub shafts 82 which are mounted by two brackets 83 which are secured to the members 71 and 72. The stub shafts 82 carry upwardly extending bars 84 which at their upper ends are turned outwardly as indicated at 85. These outwardly turned ends 85 of the bars 84 carry spring pressed pins 86 which are directed inwardly to engage in suitable openings 87 provided in flanges 88 that are provided on a cover 89. The cover 89 is secured to the members 71, 72, 73 and 74. Each of the bars 84 has connected thereto a plurality of adhesive pots 90, there being two adhesive pots for each web that passes through the device so as to apply the adhesive along both side edges of the web.

As shown, the adhesive pots 90 are bolted to the bars 84 by bolts 91 (see Figs. 5 and 9), which bolts pass through slots 92 provided in the bars. This arrangement is necessary to permit certain vertical adjustment of the adhesive pots for a purpose which will presently appear.

The adhesive pots 90 are secured at the sides opposite the bolts 91 by means of rods 93 which are mounted upon the upright frame members 71, 72, 73 and 74. These rods 93 are carried by inwardly projecting portions 71', 72', 73' and 74' integral with the frame members. The adhesive pots have spaced ears 94 thereon through which the rods 93 pass. The ears 94 are slotted as shown at 95 so that the adhesive pot can be lifted off of the rod 93 when it is desired to remove the same for cleaning. In removing the adhesive pot for cleaning it is of course necessary to remove the bolt 91 also. It will be observed from an inspection of Fig. 5 that the adhesive pots can be moved to the right or left from the position shown in Fig. 5 by swinging the arms or bars 84 about their pivot points on the stub shafts 82. The spacing of the adhesive pots and the curvature of the arms 84 are such that the adjustment of the pots can be made to correspond to adjustment of the overlapping of the leading edges of the webs 15a to 15e, inclusive. It is believed to be clear that if the leading edges of the webs 15b, 15c, 15d and 15e are set back a distance of three of the pins 81 on the drum 79 instead of two as shown in Fig. 10. The adhesive pots, in order to properly align, would have to be moved progressively further back from the lower pot to the upper pot in order to have the adhesive applying fingers in the proper position with respect to the transverse slits 36 in their respective webs.

In order to apply adhesive from the adhesive pots to a web passing over them I provide in each adhesive pot a plurality of fingers 96. The fingers 96 are mounted upon a sleeve 97 (see Fig. 6) that is keyed to a shaft 98 which extends across the adhesive pot and which is journaled in bearings 99 provided on the members 71, 72, 73 and 74. It will be understood of course that there is a shaft 98 and a set of fingers 96 for each adhesive pot. The adhesive pots are preferably provided with notches 100 in their side edges so that the shafts 98 may extend down below the top level of the pots.

The adhesive applying fingers 96 must be rocked between a lower position where they dip into the adhesive within the pots to a raised position where they contact the under surface of a web extending between the rollers 64 and 65. The means for rocking the fingers are shown best in Figs. 5 and 8. Each of the shafts 98 has affixed thereto a lever arm 101. The several lever arms 101 extend outwardly to engage pins 102 which are provided upon vertically reciprocating bars 103. The ends of the lever arms 101 are bifurcated as indicated at 104 to receive the pins 102. The bars 103 are guided vertically by guide brackets 105 and 106. The brackets 105 and 106 are mounted upon the members 73 and 74. In order to vertically reciprocate the bars 103 I provide these bars at their lower ends with cam rollers 107, which cam rollers are adapted to engage two oppositely disposed cams 108 that are fixed upon a shaft 109. The bars 103 are urged downwardly by two springs 103' which have one end attached to the bars and the other end attached to the members 73 and 74. The shaft 109 is carried by two bearing brackets 110 and

111 mounted on the members 73 and 74, respectively. The shaft 109 also carries a sprocket wheel 112 which is driven by a sprocket chain 113. The sprocket chain 113 is in turn driven by a sprocket wheel 114 mounted on a shaft 115 of a speed reducing unit 116 that is driven from a motor 117. The shaft 115 also has a sprocket wheel 118 thereon which drives a chain 119 that in turn engages a sprocket wheel 120 fixed to the drum 79.

Referring now to Figs. 5, 6, 10, 11 and 12, these figures illustrate the means by which the webs are drawn from the rollers 39 through the adhesive applying device and then trimmed so as to convert the webs into a series of separate unit strip assemblies. The drum 79 as shown is provided with four annular grooves 121, 122, 123 and 124 (see Fig. 11). The grooves 121 and 122 carry circular knives 125 and 126. The grooves 123 and 124 are adapted to receive stripper bars 127 and 128. The knives 125 and 126 are made accessible for replacement and resharpening by providing the drum 79 with removable end rings 129 and 130. These end rings are also the parts of the drum which carry the pins 81. Cooperating with the knives 125 and 126 are two exterior knives or cutters 131 and 132. The knives 131 and 132 are fixed on a shaft 133 which is journaled in the side frames 78. The shaft 133 has a pinion 134 fixed thereon. The pinion 134 meshes with a gear 135 that is fixed to the hub 136 of the drum 79 by means of screws 137. The gears 134 and 135 serve to effect rotation of the knives 131 and 132 at the same peripheral speed as the peripheral speed of the drum 79. The sprocket wheel 120 is fixed to the other hub 138 of the drum 79 by screws 139.

In order to press the webs 15a, etc. together as they are drawn about the drum 79 I provide two rollers 140 and 141. These rollers are fixed on a shaft 142 which in turn is carried by and journaled in two arms 143 and 144 that are fixed on a shaft 145. The shaft 145 is journaled in the side frames 78. The arms 143 and 144 are pressed in a direction to cause the rollers 140 and 141 to bear against the webs by two springs 146 and 147 in the manner illustrated in Figs. 5 and 12. When the webs are being applied to the pins 81 on the drum 79 it is necessary to lift the rollers 140 and 141 away from the drum 79. I therefore provide the shaft 145 with a lever arm 148. The lever arm 148 is fixed to the shaft 145 and it carries a latch member 149 which can be hooked over the shaft 133 to thus hold the rollers 140 and 141 away from the drum.

The stripper bars 127 and 128 are carried upon a cross bar 150 that extends between the side frames 78 and is fastened to the side frames. These strippers are utilized to lift the intermediate portion of the webs away from the drum after the side edges thereof have been trimmed off. Guide channels are provided at 151 and 152 adjacent the side frames 78 to direct the trimmings downwardly out of the way. In order to carry the intermediate or unit strip assembly portion of the webs away from the drum 79 a conveyor 153 may be utilized. This conveyor is not shown in detail since any suitable conveyor is acceptable for this purpose. As shown, the conveyor comprises a belt 154 which travels over a roller 155 carried by a shaft 156 that is journaled in the side frames 78. The members 151 and 152 which provide the pockets for the trimmings act also as side guides for the belt 154 and may be ex-

tended along the conveyor as far as is necessary. As shown, these members 151 and 152 are merely metal strips having one end secured to the side frames 78 and having the other end secured to some part of the conveyor not shown.

Referring now to Fig. 7, the assembly of the several webs 15a, 15b, 15c, 15d and 15e is shown as it would appear after the several webs have been brought together on the drum 79. The web assembly has been cut along the line where the adhesive has been applied to one surface of each web. The adhesive is indicated by the dots 157. The transverse slits are shown as extending outwardly beyond the line of the dots 157. It will be noted that due to the proper spacing of the adhesive applying fingers and the adhesive pots the dots 157 on the under surface of the web 15e appear in regular groups of four between the transverse slits 36. Likewise the adhesive dots 157 as applied to the under surface of the web 15d appear in regular groups of four between the transverse slits 36 of the web 15d. The same is true of the webs 15c and 15b. The web 15a being the bottom web does not need to have adhesive applied thereto. This is shown clearly by Fig. 8 where it is evident that no adhesive is applied to the under surface of the web 15a. After both side edges of the assembled webs are trimmed off the assembly of webs separates along the lines of the transverse slits 36 into unit strip assemblies all of the same size, with the individual sheets thereof adhered together by the dots 157 of adhesive along both their edges. The knives of course cut the webs between the line of the adhesive dots and the adjacent ends of the transverse slits 36 leaving the adhesive dots on the intermediate portion but removing the punched edges and cutting far enough inward from the punched edges to intersect the transverse slits 36.

In applying the adhesive by means of the fingers 96 it is desirable to back up the web while it is passing over the fingers and therefore I provide a depending bar 158 on the under surface of each of the adhesive pots 90 except the two lower ones (see Fig. 9). The cover 89 is provided with two depending bars 158' like the bars 158 to provide backing for the top web when all of the glue pots are used. The bars 158 and 158' are of just such depth as to permit ready clearance of the webs when they are drawn taut between the rollers 64 and 65. After the adhesive is applied it must not be spread or scattered by the rollers 65 so I provide these rollers with sections of reduced diameter indicated at 159 and 160 in Fig. 8 of the drawings. The adhesive dots therefore are carried, without any disturbance, from their point of application until the webs are brought together on the drum 79. When the webs are brought together the rollers 140 and 141 ride upon the portions of the webs that carry the adhesive dots and thus force the webs firmly together at this point, making sure that the adhesive dots will cause the two engaging faces of the webs to stick together.

This apparatus is a continuous feed apparatus. That is to say, the drum 79 is rotated continuously. The adhesive fingers 96 therefore have to be engaged with the webs and retracted quickly in order to avoid streaking or smearing of the adhesive lengthwise of the web. The cams 108 are so designed as to effect this type of operation. It will be noted that the cams are notched at 108a (see Fig. 5) so that when the rollers 107 ride into the notches 108a the bars 103 are dropped suddenly to the full extent of the drop

75

necessary to bring the fingers 96 up against the webs. Then immediately the bars 103 are again raised slightly to withdraw the fingers from engagement with the webs with a very quick action.

5 In this fashion the fingers are caused to apply the adhesive to the webs so quickly that there is very slight longitudinal movement of the webs while the fingers are in engagement therewith. After the fingers are disengaged from the webs they are of course slowly lowered into the adhesive so that they again will be adequately coated for the next engagement with the webs.

The construction is such that the adhesive pots can be removed for cleaning and refilling without difficulty. The side walls 67 and 68 are hinged to the frame members 71 and 72 as indicated at 67' and 68' so that they may be swung open to permit ready access to the adhesive applying mechanism. It will also be noted from Fig. 9 that the side walls 67 and 68 are cut out to permit the outwardly turned portion 85 of the bars 84 to pass.

From the foregoing description it is believed that the nature and advantages of the present invention will be readily apparent to those skilled in this art.

Having thus described my invention, what I claim as new and desire to secure by Letters Patent is:

30 1. The method of making unit strips which comprises transversely slitting a web of paper from a point spaced from one margin of the web to a point spaced from the other margin thereof at uniformly spaced points along its length and thereafter attaching the leading edges of a series of lengths of the transversely slit web each in fixed relation to a common advancing member in such way that the slits are offset from top to bottom of the several lengths, applying securing means to the overlapped lengths between but spaced from the lines of severance provided by the slits whereby to secure the corresponding portions of the several lengths to each other, and thereafter cutting off the side edges of the overlapped lengths at points spaced further from the margins of said web than the ends of said slits.

40 2. The method of making unit strips, which comprises transversely slitting webs of paper at uniformly spaced points along the length thereof, with slits terminating short of the side edges to leave continuous marginal connecting portions beyond the ends of said slits, superposing a group of webs with the transverse slits therein progressively offset lengthwise of the webs from one face of the group to the other, securing the individual webs to the adjacent webs along the length of the group at points inwardly from the ends of said slits so that the portion of each web between two transverse slits is secured to only one corresponding portion of the adjacent web engaged with a face thereof, and separating the assembled webs into groups of sheets by cuts longitudinally of the webs intersecting the slits near their ends outwardly from said point of securing.

50 3. The method of making unit strips, which comprises transversely slitting webs of paper at uniformly spaced points along the length thereof, with slits terminating short of the side edges to leave continuous marginal connecting portions beyond the ends of said slits, superposing the webs with the transverse slits therein progressively offset lengthwise of the webs from one face of the group of webs to the other, securing

the two contacting faces of the adjacent webs to each other by applying adhesive to at least one of the contacting faces in the area between but spaced from the nearest adjacent transverse slits of both webs and spaced inwardly from the ends thereof, and separating the assembled webs into unit strip assemblies by separating the marginal connecting portions from said webs between said areas and the ends of said slits.

4. The method of making unit strips, which comprises transversely slitting webs of paper at uniformly spaced points along the length thereof, with slits terminating short of the side edges to leave continuous marginal connecting portions, superposing a group of webs with the transverse slits therein progressively offset lengthwise of the webs from one face of the group to the other, securing the webs to each other at points inwardly of the ends of the slits by applying longitudinally extending areas of adhesive just inwardly of the ends of the slits adjacent one side edge of the assembled webs, then trimming off the marginal connecting portions of the webs outwardly from said points but inwardly of the ends of said slits to separate them into groups of overlapped sheets.

5. The method of making unit strips, which comprises transversely slitting webs of paper at uniformly spaced points along the length thereof, with slits terminating short of the side edges to leave continuous marginal connecting portions, superposing a group of webs with the transverse slits therein progressively offset lengthwise of the webs from one face of the group to the other, securing the webs to each other at points inwardly of the ends of the slits by applying longitudinally extending areas of adhesive just inwardly of the ends of the slits adjacent both side edges of the assembled webs, then trimming off the marginal connecting portions of the webs outwardly from said points but inwardly of the ends of said slits to separate them into groups of overlapped sheets.

6. A machine of the character described, comprising vertically spaced pairs of horizontally separated rollers adapted to support and guide a plurality of webs in vertically spaced paths, means for drawing the webs across said rollers and pressing them together after leaving said rollers, and adhesive applying means interposed between the paths of the webs over said rollers and operable to apply adhesive to the webs in passing from one roller of a pair to the other roller of said pair, said adhesive applying means each including fingers engaging the under surfaces of the webs and bars above the webs opposite said fingers, and means for simultaneously moving said fingers into engagement with a plurality of said webs.

7. A machine of the character described comprising a rotary member adapted to receive, advance and positively position a plurality of webs in a predetermined superposed relationship, means on said member engaging each of said webs to hold said webs positively in position on

said rotary member, means for mounting said webs to guide the same in spaced paths to said member, means for applying adhesive to said webs while spaced, means cooperating with said web receiving member to press all said webs together, and means cooperating with said web receiving member while said webs are engaged with said positive positioning means to trim the edges of said webs while superposed after being pressed together.

8. A machine of the character described comprising a rotary member adapted to receive, advance, and position a plurality of webs in a predetermined superposed relationship, means on said member engaging each of said webs to hold said webs positively in position on said rotary member, means for mounting said webs to guide the same in spaced paths to said member, means for applying adhesive to said webs while spaced, means cooperating with said web receiving member to press all said webs together, means cooperating with said web receiving member while said webs are engaged with said positive positioning means to trim the edges of said webs while superposed after being pressed together, and a pair of laterally outwardly directed guide members cooperating with said rotary member to guide the resulting trimmings away from said web.
9. A machine for producing assemblies of sheets from webs provided with transverse slits terminating short of the side edges thereof, comprising means supporting said webs in spaced relation, an advancing member having means engaging said webs adjacent both margins thereof to draw said webs from the supporting means and relatively position the same, and means cooperating with said member to press all of said webs together simultaneously, adhesive applying means between the webs supported by said first named means, and side edge trimmers comprising cutter members on said advancing member and cutter members cooperating therewith engaging the pressed together webs on said advancing member and removing the uncut side edges of the webs.

ANDREW L. ERICKSON.
